W. W. TEAGUE

EXPANSIBLE FORM

Filed Aug. 20, 1923

W. W. Teague,

INVENTOR

BY *Victor J. Evans*

ATTORNEY

W. May. Dinsall.

WITNESSES

UNITED STATES PATENT OFFICE.

WEBSTER WELCH TEAGUE, OF MARION, INDIANA.

EXPANSIBLE FORM.

Application filed August 20, 1923. Serial No. 658,476.

To all whom it may concern:

Be it known that I, WEBSTER W. TEAGUE, a citizen of the United States, residing at Marion, in the county of Grant and State 5 of Indiana, have invented new and useful Improvements in Expansible Forms, of which the following is a specification.

The object of this invention is to provide an expansible form, or drum upon 10 which fibrous material may be wound by the use of a suitable machine, for producing fibrous or paper receptacles or containers for products of various kinds.

A further object is to provide a form or 15 drum comprising a plurality of semi-cylindrical elements adapted to be positioned for serving as a form for a receptacle of a given size, with novel means for drawing these elements together and reducing the 20 size of the form, or the circumference of the cylinder, to facilitate removal from the receptacle after the latter has been built up by the winding movement of a plurality of sheets of fibrous material, suitable for the 25 purpose.

A still further object is to provide one of the semi-cylindrical elements with transverse braces having shaft bearings formed therein, means for mounting the semi-cylindrical 30 elements for movement with reference to each other, and adjustable devices for controlling such movement.

With the foregoing and other objects in view, the invention consists in the novel 35 construction and arrangement of elements described and claimed, it being understood that modifications may be made within the scope of the claims without departing from the spirit of the invention.

In the drawings, Figure 1 is an end view 40 of the device; Figure 2 is a section on line 2-2 of Figure 1; Figure 3 is a longitudinal section through the semi-cylindrical elements, with the interior structure in plan.

The semi-cylindrical elements of the form 45 are designated 10 and 12, and element 10 is provided with rigidly mounted transverse braces 13 and 14 having hub portions 15 providing bearings for shaft 16. Each

transverse brace includes an inwardly and laterally extending element 17 through 50 which rivets are passed into element 10, and each brace also includes an offset 18 provided with a slot 19 engaged by a pin 20.

The pins are rigid with reference to element 55 12 and project inwardly therefrom, and the

slots limit the degree of expansion and contraction of the form.

Collars 21, 22 are carried by the shaft, adjacent to each brace, and in the position 60 shown, being retained by set screws 23. These collars are each threaded at 24 and receive one end of adjusting screw 25 having a milled central disk portion 26, permitting of adjustment by hand. The opposite 65 end of the screw is reversely threaded and enters a threaded bore 27 in socket member 28 projecting inwardly from element 12 and rigid therewith.

It will therefore be observed that element 70 12 is movable with reference to element 10 and the transverse braces, for the purpose of decreasing the circumference of the form after the winding operation incident to the 75 formation of the receptacle or container. The contracted form may be readily removed from the completed article. Particular emphasis is placed on the simplicity of the construction, the positive action, and the positive manner in which the form is maintained in an established position, the elements being absolutely rigid at any adjustment within the limit of the construction. 80

What is claimed is:—

1. A device of the class described, comprising a pair of semi-cylindrical elements, 85 braces extending across one of said elements and rigid therewith, said braces including shaft bearings, and means for adjustably mounting the other of said semi-cylindrical 90 elements with reference to that first named and with reference to said braces.

2. A device of the class described, comprising a pair of semi-cylindrical elements, 95 braces extending across one of said elements and rigid therewith, said braces including shaft bearings, means for adjustably mounting the other of said semi-cylindrical elements with reference to that first named and with reference to said braces, and 100 means for guiding and limiting movement of the second named semi-cylindrical element.

3. A device of the class described, comprising a pair of complementary form elements, a brace extending transversely and rigidly with reference to one of said elements, a shaft extending through the brace, a collar rigid on the shaft, and a reversely threaded device passing into the collar and 105 having connection with the remaining element of the form. 110

4. A device of the class described, comprising a pair of form elements, transverse braces rigid with reference to one of said elements, said braces each including an outer slotted portion, pins projecting from the inner side of the other form element and entering the slots, a shaft extending through the braces, collars rigid on the shaft, threaded socket members on the in-

ner surface of that form element having the pin, and a reversely threaded adjusting device connecting each collar with one of the socket members for varying the relative position of the form elements, and the expansion and contraction of the form.

15

In testimony whereof I affix my signature.

WEBSTER WELCH TEAGUE.
